UNITED STATES PATENT OFFICE.

HARRY D. LOCKWOOD, OF KANSAS CITY, KANSAS.

BABY-CHICKEN BROODER.

Application filed July 30, 1925. Serial No. 47,056.

This invention relates to a housing for baby chickens and particularly to cabinets used in retail stores for displaying the chickens to be sold, and the primary object 5 of the invention is the provision of a cabinet for baby chickens that will be effective in keeping the chickens warm, well fed and clean.

Heretofore, it has been customary to move 10 baby chickens from one box to another when it was desired to change the litter. This invention contemplates the construction of a cabinet which is adapted to automatically dump the dirty litter into a suitable container 15 as clean, new litter is spread over the floor of the cabinet.

A further object of the present invention is the provision of a housing for baby chickens which has a means for keeping the chickens 20 warm and changing the litter without the harmful practice of handling the chickens as high as three or four times a day.

A still further object of this invention is the provision of a simply constructed cabinet 25 for carrying out the above broader objects, as well as to embody many minor objects and refinements of construction illustrated in the accompanying drawings in which:

30 Figure 1 is a perspective view of a chicken housing constructed in accordance with this invention.

Fig. 2 is a vertical central section of the chicken housing.

35 Fig. 3 is a vertical cross section of the same taken on line III—III of Fig. 2.

Fig. 4 is a vertical section of the device taken on line IV—IV of Fig. 3.

40 Fig. 5 is a side elevation of the cabinet with the sheet-metal housing removed and broken away to show the heating means.

Fig. 6 is a cross section of the cabinet taken on line VI—VI of Fig. 2.

45 Fig. 7 is an enlarged, fragmentary, detailed, sectional view of the means for engaging and turning the roller operating rod, and,

Fig. 8 is a wiring diagram of the circuit used in the display cabinet.

50 Referring at this time to the drawings in detail, wherein similar reference characters refer to like parts throughout the several views, the numeral 9 designates the two ends of a cabinet having sides 10. This cabinet

should be covered with glass which may be 55 in two sections 11, overlapped and adapted to slide in suitable grooves 12. The two ends of the cabinet are each provided with a clean litter magazine which is formed between ends 9 by partitions 13 which extend across 60 the cabinet from one side 10 to the other, one of which may support an ordinary feed trough as shown in Figs. 2 and 3. A door 14 may be supplied if desired and an angled apron 15 set inside to keep the clean litter 65 from falling down on each end of endless belts 16 which form the movable floor.

The floor is preferably formed of two endless belts 16 which are set in tandem with a space between their adjoining ends which are 70 substantially at the vertical center of the cabinet. Transverse rollers 17 carry belts 16 and a solid sheet metal floor 18 may be used directly beneath the upper portion of the belt to bear the weight of the baby chickens. 75

To keep the birds from falling between the two center rollers, a guard 19 is provided which may be raised when the floor is moved to dump the dirty litter into a receptacle 20, removably positioned below endless belts 16 80 as shown in Figs. 2, 3 and 6. One method of raising and lowering this guard from the outside of the cabinet is here shown to comprise a rod 21, extending along one side of the cabinet to a transverse shaft 22 to each 85 end of which is fastened, by a crank arm 23, a connection 24 leading downwardly to guard 19. The handle 25 is used to push and pull rod 21 which acts to raise and lower the guard 19. A pair of guide members 26 may 90 be provided at each end of guard 19 if desired.

Means to operate the endless belts and move the floor to dump dirty litter and spread clean litter thereover may consist of bevel 95 gears 27 rigidly carried by one end of center rollers 17. Gears 28 mesh with the drive gears 27 and are rotated by a shaft 29 leading to a point outside the cabinet to be engaged by any key or crank 30 which is formed to turn 100 the shaft in one direction only. When it is desired to clean the cabinet without removing any of the baby chickens, rod 21 is pulled to raise guard 19, rod 29 is rotated and dirty litter is carried to the center and dumped 105 into drawer 20. As this is taking place, clean litter is being spread over the belts from the magazines located at each end of the cabinet.

The supply of clean litter is also adjusted by an opening between an apron 31 and belts 16. This apron 31 is fastened to partition 13 by bolts or analogous means 32 which pass through slots 33. The opening between the upper part of belt 16 and apron 31 may be changed to be made wider or narrower as desired.

Each side 10 of the cabinet has a longitudinal opening covered by screen 34 to keep the baby chickens from escaping therethrough into sheetmetal housings 35 which are carried along each side of the cabinet to enclose the heating and temperature regulating means. One side of the cabinet 10 supports a heating means, which is preferably an electrical element 36 mounted on an asbestos or similar pad 37 and encased in a metal enclosure 38 which covers the opening in that particular side and allows air to pass therethrough and into the cabinet only after it has entered a series of openings 39 and has been heated by element 36. The air then passes across the cabinet and over the baby chickens to the opening in the other side 10 where it passes out into housing 35 and through the openings 40 formed in the top thereof.

To regulate the passage of air at a predetermined temperature, a thermostatically controlled shutter 41 may be used and slidably mounted close beneath openings 40 to open and close the same. For instance, when the temperature of the cabinet where the baby chickens are located reaches ninety degrees, the shutter 41, which is normally closed, begins to open through the energy exerted by any suitable thermostat 42 and the appropriate interconnecting leverage 43. The connection to shutter 41 may be adjusted through the connection 44 if desired. When the temperature lowers, the thermostat 42 draws the shutter closed again.

To further regulate the heat, an additional thermostat 45 may be provided which operates an electric switch 46 through any suitable leverage 47. This thermostat is set to operate or open the switch 46 when the temperature reaches ninety-five degrees. Any operative relation may be established between thermostat 42 and thermostat 45. When switch 46 is opened, the current from the source of supply 48 is cut off from the heater or resistance

coil 36, and the air entering the cabinet is not heated.

It is understood that many changes and modifications may be made in the construction of this invention without departing from the spirit of the same or the scope of the appended claims.

What is claimed is:

1. A device of the character described comprising a cabinet, a movable floor within said cabinet, means for moving said floor, means for receiving the dirty litter dumped from said floor as the same is moved and means for spreading clean litter over said floor as it is being moved, said floor adapted to dump dirty litter at the center of said cabinet as it receives clean litter at each end thereof.

2. A device of the character described comprising a cabinet, a floor movably carried therein, means for moving said floor, removable means for catching dirty litter dumped from said floor and means for spreading clean litter over said floor at each end of the cabinet as said floor is moved, said last mentioned means having a vertically adjustable plate for controlling the flow of litter to said movable floor and an angled apron disposed to direct the flow of clean litter toward said plate.

3. A device of the character described comprising a cabinet, a floor within said cabinet comprising endless belts disposed in tandem with the upper surfaces thereof in the same horizontal plane, rollers supporting said belts, means for turning said rollers from exteriorally of said cabinet and means for spreading clean litter over said belts at their remote ends as the same are caused to pass around said rollers and dump dirty litter therefrom from the adjacent ends of each of said belts.

4. A baby chicken display cabinet comprising a cabinet, a movable floor within said cabinet comprising a pair of endless belts disposed in tandem, means for moving said belts to dump dirty litter therefrom at their adjacent ends and means for selectively opening and closing the space between the adjacent ends of said belts.

In testimony whereof I hereunto affix my signature this 28th day of July, 1925.

HARRY D. LOCKWOOD.
